UNITED STATES PATENT OFFICE.

ANDY P. LUNDEEN, OF GALESBURG, ILLINOIS.

BOTTLE-CAPPING MACHINE.

Specification of Letters Patent. Patented Mar. 19, 1918.

1,260,220.

Application filed May 4, 1917. Serial No. 166,354.

To all whom it may concern:

Be it known that I, ANDY P. LUNDEEN, a citizen of the United States, and a resident of Galesburg, in the county of Knox and State of Illinois, have invented a new and useful Bottle-Capping Machine, of which the following is a specification.

My invention relates to machines for inserting paper or similar caps in milk-bottles and the like.

One of the objects of the invention is to provide a relatively inexpensive machine the price of which will not be prohibitive to the small dairies.

Another object is to provide novel means for feeding the caps successively to the capping mechanism.

Another object is to provide novel capping mechanism operating conjointly with the feeding mechanism.

Another object consists in providing novel structural features.

Still another object consists in making the machine efficient in use with bottles differing in height.

Concise stated, the principal end and object to the invention is to generally improve the construction and increase the capacity, utility and efficiency of devices of this character, and it consists, substantially, in the improvements herein shown and described.

In the accompanying drawings, which illustrate my invention as embodied in the best way now known to me, and which embodiment has been successful in practical operation:

Figure 1 is a side elevation showing the device in position to start to operate in capping a milk-bottle;

Fig. 2, a similar view, but showing the operation as having been completed;

Fig. 3, a rear elevation, the parts in the same relative positions as in Fig. 1;

Fig. 4, a top plan, illustrating by dotted lines the movement of the cap-feeder; and

Fig. 5, a vertical section, its plane taken in the line 5—5 in Fig. 4.

Coming now to a detailed description of the drawings, and indicating the elements and, where necessary, the parts thereof each by a distinguishing reference numeral, uniformly employed, 2 indicates a table on which the foot 3 of a supporting-leg 4 is secured by a bolt 5 and nut 6. The leg 4

has an elongated slot 7 in which reciprocates a pair of guide-lugs 8 projecting from the rear of face of the vertical arm of an L-shaped bracket 9. A bolt 10 passes through an aperture (which it fits) in said arm and 60 through said slot 7 and is adjustably secured to the leg 4 by a wing-nut 11. The operating lever 12 passes through a slot 13 in the bracket and is fulcrumed therein by means of a bolt 14 secured in place by a cotter 15—see Figs. 1 and 3. For convenience the vertical arm of the bracket is designated by 9', and the horizontal arm by 9''. The terminal of the arm 9 is formed into a guide-eye or bearing 16 in which reciprocates a plunger 17 hinged at its enlarged, forked upper end, by means of a pin 16', to the lever 12. Suitably secured to its lower end is a capping-head 18 having a stem 19. The lower end of a compression 75 or lever-return spring 20, which embraces the plunger, rests on the eye 16 and its upper bears against a washer 21 which rests beneath the enlarged upper end of the plunger.

The device hereinbefore described may be efficiently operated as a bottle-capping device, the caps being each fed by hand, or manually. In using it, a bottle 22 is placed in proper position, as shown, and a cap 23 85 laid in the upper portion of its mouth. Upon operating the lever 12 the plunger 17 will be forced down to thereby drive the head 18 onto the cap 23, and a completion of the throw of the lever will force the cap 90 onto its seat 24 in the neck of the bottle. Upon release of the lever the spring 20 will return it and also the plunger and capping-head to their normal positions, ready for another operation.

25 indicates a cap-holding cylinder secured to the bracket-arm 9' by a clip 26 or in any other desired manner. Its bottom is formed by a pair of substantially quadrant shaped pieces 27 spaced from each other to 100 provide a way 28. The front half, or thereabout, of the lower end of the cylinder is open, as indicated at 29, Fig. 4. On the outer lower edge of the cylinder is a cap-guiding tongue 30 which consists of a strip 105 of sheet metal preferably soldered at one of its ends to the cylinder, its other end projecting slightly past the part 31 now to be described.

31 designates the upper portion of the bot- 110

tom of an inclined chute the lower portion 32 of which has a less degree of inclination. 33 indicates a bottle-neck guide-ring having an annular flange 34. At its rear portion 5 said ring is provided with a cap-guiding projection 35 which is soldered to the lower terminal of the part 32. The projection 35 consists preferably of a small piece of sheet metal, transversely curved, the free edge of 10 which overlies the adjacent edge of the flange 34 and the ends of which are preferably soldered to the cheeks of the element 32. 36 indicates a guard suitably secured, as by soldering, to the sides 31' of the chute bottom 31. 37, 37 indicate guide-rods each fixed at its lower end to the guide-ring 33 and each reciprocable in registering eyes in brackets 38 secured to the stem 19 by screw-bolts 39. 40, 40 designate relief-springs, 15 each embracing one of said rods 37, the upper end of each resting against the lower face of the upper eye of the adjacent bracket 38 and its lower end on a cross-pin 41 projected transversely through a rod 37, as 20 shown best in Fig. 2.

Secured by a bolt 42 to the bracket-arm 9" is a guide-bracket 43 having perforated upturned terminals 44, 45, 46. 47 indicates a bar reciprocatory in said eyes. One of its 25 end portions is directed transversely and thence forwardly to form a cap-picking finger 48 and the other end, 49, is turned laterally to engage a slot 50 in the power arm 51 of a bell-crank lever fulcrumed at 52 to a supporting arm 53 fixed by a screw-bolt 54 to the arm 9". 55 indicates a pin projecting from one of the brackets 38 and extending through a slot 56 in the arm 57 of the bell-crank lever.

40 Preferably a weight 58 or some other means is used to bear upon the caps in the cylinder 25, not only in order that they may feed properly but also to prevent them from warping and becoming saucer shaped.

45 The operation is illustrated best in Figs. 1 and 2. As the lever 12 is depressed the plunger 17 and head 18 will be simultaneously depressed, as hereinbefore described, and a cap, previously placed in the bottle-mouth, will be pressed down onto its seat, also as before described. Upon release of the lever the head 18 will rise and the elements will shift from the positions shown in Fig. 2 to those shown in Fig. 1, the pin 55 causing the bell-crank lever arm 51 to move relatively outward to thereby draw upon the terminal 49 of the rod 47, thus causing the finger 48 to move in the same direction, and in so moving it will draw with it the bottom one of the caps 23 in the cylinder 25. The cap will be guided by the tongue 30 and the progressively-stepped chute 31, 32 and 35, and its momentum will carry it to proper position to be operated 60 upon. Upon actuation of the lever the cap-

ring flange 34 will be forced down to rest lightly upon the top of the neck of the bottle, the relief springs 40 absorbing the force of the sudden stop. The plunger will, due to continued pressure on the lever 12, continue in its downward movement, forcing the cap firmly onto its seat. There will be no sudden impact, however, for the relatively strong resistance spring 20 prevents such. 75

Adjustments of the bracket 9 by means of the bolt 10 and wing-nut 11 may be quickly made to accommodate bottles differing materially in their heights, as, for instance, pints, quarts and half-gallons. Slight differences, such as frequently occur in bottles having the same capacity, are immaterial. 80

I realize that considerable variation is possible in the details of this construction without departing from the spirit of my invention; therefore I do not intend to limit myself to the specific form shown and described, except as pointed out in the appended claims, wherein it is my intention to claim as broadly as is permitted by the state 90 of the art all the novelty inherent in the invention.

I claim as new the following, to-wit:

1. In a bottle-capping machine, a plunger, an element in which it may be reciprocated, a head operated by the plunger, a cap-containing receptacle having a narrow slot in its bottom, a rod-like cap-picking finger operating in said receptacle, and means whereby the plunger and finger are 100 simultaneously operated.

2. In a bottle-capping machine, a base, an arm secured thereto and provided with a bearing-eye, a plunger working in said eye, a capping-head secured to the plunger, means for operating the plunger downward, means for returning it to normal position, a bell-crank lever pivotally connected to said head, and a cap-picking finger operable by said lever. 105

3. In a bottle-capping machine, a base, an arm secured thereto and provided with a bearing-eye, a reciprocable plunger working in said eye, a capping-head secured to the plunger, a bell-crank lever pivotally connected to the head, a guide-bracket having a plurality of eyes, and a cap-picker reciprocable in said eyes and operable by said lever. 115

4. In a bottle-capping machine, a base, an arm secured thereto and provided with a bearing-eye, a reciprocable plunger working in said eye, a capping-head secured to the plunger, a supporting-arm secured to the arm above recited, a bell-crank lever fulcrumed in the supporting arm and pivotally 125 connected with said head, and a cap-picking finger operable by said lever.

5. In a bottle-capping machine, a base, an arm secured thereto and provided with a bearing-eye, a reciprocable plunger working 130

in said eye, a capping-head secured to the plunger, a supporting-arm secured to the arm above recited, a bell-crank lever fulcrumed in the supporting-arm and pivotally connected with said head whereby to rock it, a cap-holding cylinder, and a cap-picking finger operable by said lever and traversing the bottom of said cylinder.

6. In a bottle-capping machine, a vertically arranged base, a bracket adjustable vertically thereon, an operating-lever pivoted in the bracket, a plunger reciprocable in an eye in the bracket and operated in one

movement by said lever, a capping-head secured to the plunger, a cap-holding cylinder, 15 a chute leading therefrom to the bottom of said head, an arm secured to said head, a bell-crank lever fulcrumed in said arm and pivotally connected with said head, and a cap-picking device one end of which is connected to and operable by the bell-crank lever and the other end of which has a finger reciprocating in the bottom of the cylinder.

In testimony whereof I hereto affix my signature this 27th day of April, 1917.

ANDY P. LUNDEEN.
